Attorney.

UNITED STATES PATENT OFFICE.

HENRY C. RIEHLE, OF DOWNS GROVE, ILLINOIS, ASSIGNOR TO STANDARD ASPHALT & REFINING COMPANY, OF CHICAGO, ILLINOIS, A CORPORATION OF DELAWARE.

DESIGN FOR AN EXPANSION-JOINT FILLER FOR PAVING AND BUILDING PURPOSES.

56,729.

Specification for Design.

Patented Dec. 7, 1920.

Application filed May 17, 1918. Serial No. 235,201. Term of patent 14 years.

To all whom it may concern:

Be it known that I, HENRY C. RIEHLE, citizen of the United States, residing at Downers Grove, in the county of DuPage and State of Illinois, have invented a new, original, and ornamental Design for Expansion-Joint Fillers for Paving and Building Purposes, of which the following is a specification, reference being had to the accompanying drawing, forming part thereof.

Figure 1 is a perspective view of an expansion joint filler for paving and building purposes, showing my new design.

Fig. 2 is a vertical longitudinal section of the same.

The expansion joint filler for pavements, as shown, consists of a comparatively long and narrow body or strip of any suitable adhesive and elastic material, such as as-

phaltum, or the like, the upper portion of the body being of greater thickness than the lower portion and of substantially less width than the latter, so that the body is substantially T-shaped in cross-section. Co-extensive with the opposite faces of the lower portion of the body are layers of a compressible material, such as felt or the like, and the outer faces of the felt layers are flush with or lie in the plane of the opposite side faces of the upper portion of the body.

I claim:

The ornamental design for an expansion joint filler for paving and building purposes, as shown.

In testimony whereof I affix my signature.

HENRY C. RIEHLE.
